UNITED STATES PATENT OFFICE.

WARREN MCARTHUR, OF CHICAGO, ILLINOIS.

DESIGN FOR A HEATING-STOVE.

SPECIFICATION forming part of Design No. 23,877, dated December 11, 1894.

Application filed August 3, 1894. Serial No. 519,420. Term of patent 3½ years.

To all whom it may concern:

Be it known that I, WARREN MCARTHUR, a citizen of the United States, residing in the city of Chicago, county of Cook, and State of Illinois, have invented and produced a new and original Design for Heating-Stoves in which Oil or Gas is Burned, of which the following is a specification, reference being had to the accompanying drawing, forming a part thereof.

The characteristic feature of my design con-

sists in the combination of four distinct radiating flues connected with a common top and base substantially as shown in the accompanying drawing.
